Attorney.

UNITED STATES PATENT OFFICE.

H WALTER ALEXANDER, OF SAC CITY, IOWA, ASSIGNOR TO B. R. GREENBLATT, OF OMAHA, NEBRASKA.

RING-MOLD.

1,280,128.

Specification of Letters Patent.

Patented Oct. 1, 1918.

Application filed February 13, 1917. Serial No. 148,441.

To all whom it may concern:

Be it known that I, H WALTER ALEXANDER, a citizen of the United States, and a resident of Sac City, in the county of Sac 5 and State of Iowa, have invented certain new and useful Improvements in Ring-Molds, of which the following is a specification.

My invention relates to molds for casting metal, and particularly to molds for casting finger-rings and the like from precious metals such as gold. The general object of my invention is to provide a permanent mold for casting finger-rings, the mold being 10 adapted for producing a ring having a crown or bezel for receiving a jewel, and the body of the ring being shaped to facilitate rolling or swaging operations thereon for varying the size thereof after it is cast. 15 A further object of my invention is to provide, for molds of this class, a head or crown-core having internal vents for the prong-channels, whereby there may be attained a perfect flow of the molten metal 20 into said prong-channels. Further objects of my invention are to provide special venting means for the main mold-cavity, to provide simple and convenient means for supporting the mold-parts in assembled relation, 25 and to provide a mold of the class described 30 in which the main body-portion is of hard argillaceous material and of a form substantially concentric with the mold-cavity, and thereby to avoid cracking or checking of 35 the mold by unequal expansion thereof when the same is heated.

In the accompanying drawings Figure 1 is an axial section of a mold embodying my invention, Fig. 2 is a front view thereof 40 with the center-core and the front half of the mold removed, Fig. 3 is a section in the horizontal plane of the line 3—3 of Fig. 2, Fig. 4 is a detail side view of the crown-core, and Fig. 5 is a vertical section on the 45 plane of the line 5—5 of Fig. 4.

The main body of the mold provided by my invention is preferably of hard argillaceous material, being a composition of clay, hardened by drying and by firing in a suitable kiln. The general form of the mold is 50 preferably cylindrical, being substantially concentric with the annular mold-cavity, so that there is approximately a uniform thickness of material around the outer sides 55 of the mold-cavity. Extending axially of

the mold-body there is a tapering or truncconical opening adapted to receive a metallic expanding and contracting core, such as that shown in U. S. Letters Patent No. 1,183,515, issued to me May 16, 1916. The 60 axially-perforate cylindrical mold-body is preferably parted in the plane of the mold-cavity to form front and rear annular mold-portions 6 and 7, the mold-cavity being formed by recesses 8 and 9 in the adjacent 65 faces of the parts, adjoining the bore thereof. When the front and rear mold-parts 6 and 7 are assembled they are held in coaxial relation by the core 10, of which the structure and mode of operation are fully set 70 forth in the Letters Patent above mentioned. The mold-parts 6 and 7 are surrounded peripherally by metal clamp-bands 11 and 12, the ends of said bands being turned outwardly and being drawn toward each 75 other by a clamp-screw 13, as shown in Fig. 2. The clamp-band 12 has at opposite sides thereof hooked projecting side-pieces 14 adapted to engage slidably the parallel side-portions of a supporting frame 80 formed by a U-shaped rod or heavy wire 15, said supporting frame being held in a vertical position by any suitable means. The mold-parts are held together axially by means of two or more resilient split-rings 16, 85 which extend around the mold so that their ends bear against the front and rear faces thereof, as indicated in Fig. 1.

At the upper side of the mold there is a gate or pouring-channel formed by recesses 90 17 in the adjoining faces of the parts 6 and 7, said channel being approximately conical and tapering from the upper to the lower end, where it joins the mold-cavity formed by the recesses 8 and 9. A main vent, for the escape of air and gas from the mold-cavity, 95 is formed by radial channels 18 in the adjoining faces of the mold-parts, the same preferably being disposed at the upper part of the mold near one side of the pouring-channel, as shown in Fig. 2. A further venting means is provided, consisting of shallow channels *a* formed in the adjoining faces of the parts 6 and 7, said channels *a* not communicating directly with the mold 100 cavity but extending concentrically therewith and having radial portions *b* extending to the peripheral edges of the mold. The channels *a* and *b* form passages for the escape of air and gas from the pores or in- 110

terstices of the material forming the mold, and also permit the free escape of any gases that may pass out from the mold-cavity at the parting-plane between the contacting 5 faces *c* around the mold-cavity. It will be understood that while said faces *c* fit together so closely as to prevent escape of molten metal from the mold-cavity, or the formation of a fin on the casting, the contact 10 between said surfaces is, in practice, not necessarily such as to form a gas-tight joint, and the escape of gases through said joint is facilitated by reducing to a minimum the radial distance traversed thereby before reaching a clear or unobstructed space, such as that afforded by the channel *a*.

When the mold is to be used for casting rings having a bezel or crown, for receiving a jewel or setting, there is provided in the 20 parts 6 and 7 a trunco-conical recess of which the axis extends vertically in the parting plane of the mold, and of which the smaller end connects with the mold-cavity, while the larger end extends to the lower 25 side of the mold. In said recess there is disposed a metal crown-core of which the form is shown in detail in Figs. 4 and 5. Said crown-core has a trunco-conical upper end-portion 19 which extends through the mold- 30 cavity into contact with the center-core 10, and the main body 20 of the crown-core has in its upper portion a plurality of prong-channels 21 of which the inner sides lie in a cone-surface formed by downward prolongation 35 of the upper end-portion 19. From the inner side of each of the prong-channels a vent-slit 22 extends in radially of the core-axis and communicates with a central conical cavity or recess 23 in the core-body, said 40 cavity or recess being open at the bottom. Pins 24, integral with the core-body, extend downwardly therefrom and rest upon a metal shelf 25 of which the end-portions are secured to the support 15. The prong-channels 45 of the crown-core are usually six in number, and to insure the positioning of the core in the mold so that the crown-prongs will be symmetrical to the plane of the ring, there is provided a pin 26 passing transversely through the core near the lower end 50 thereof, the ends of said pin fitting into recesses therefor in the mold-parts at the parting-plane, as shown in Fig. 2. The vent-slits 22 extend substantially the full length 55 of the prong-channels, and said slits are made so narrow that the molten metal flowing into the prong-channels will not flow through the slits into the central cavity 23 of the core. In making the core, the vent-slits 60 may be conveniently formed by the use of a very thin circular saw of a diameter such as indicated by the curvature of the upper and lower ends of the slits indicated in Fig. 5.

65 In the use of the mold, when the molten

metal is poured into the mold-cavity and flows into the prong-channels 21, all air or gas in said channels may readily escape through the vent-slits, and cannot in any way be trapped therein, so that perfectly-cast-prongs may be obtained for the bezel or crown of the ring. In molds of this class heretofore produced, it has been customary to vent the prong-channels at the lower ends thereof, but with such venting the castings 75 produced are often rendered defective by having blow-holes in the sides of the prongs, particularly on the inner sides thereof near the point of their juncture with the main body of the ring. Such blow-holes are entirely avoided by the use of the centrally-vented crown-core.

It may be noted that, in the mold shown, the mold-cavity is so formed that the ring produced therein will have an extra thickness of material at the side adjoining the crown, and also at the side diametrically opposite the crown. The latter material is provided to enable the enlargement of the ring by rolling or swaging thereof after it 90 is cast, without reducing the normal thickness of metal therein, which is that provided at the points intermediate the thickened portions.

From the foregoing it will be seen that 95 my invention provides a convenient and efficient finger-ring mold for goldsmiths' and jewelers' use, in which all the parts are substantially permanent and capable of repeated use without appreciable deterioration. 100 It will also be seen that by the special venting means employed therein, it is possible to produce invariably a perfectly-cast ring, requiring only the removal of the sprue and the usual polishing to complete the same 105 ready for receiving a jewel or setting.

Now, having described my invention, what I claim and desire to secure by Letters Patent is:

1. In a finger-ring mold, a crown-core 110 comprising a hollow conical metal body having prong-channels in the outer portion thereof and vent-slits extending from the inner sides of said prong-channels to the central cavity of the body.

2. In a finger-ring mold, a crown-core comprising a trunco-conical body of metal, having an open central cavity, there being longitudinally extending prong-channels on the outer side of the body, and continuous 120 vents extending longitudinally of said prong-channels and communicating with the central cavity.

3. In a ring-mold, the combination with mold-parts having an annular mold-cavity 125 and a trunco-conical core-recess communicating with one side of the mold-cavity, of a crown-core fitting in said recess and forming the inner wall of channels for crown-prongs, said core having a central opening 130

and vents connecting said central opening with the adjacent sides of the prong-channels substantially throughout their length.

4. A permanent mold for finger-rings, comprising annular mold-parts having a parting-plane perpendicular to the axis thereof, a center-core extending through the central openings of said mold-parts to aline them axially, the mold-parts being recessed 10 at the parting-plane to form an annular mold-cavity around the center-core and to form a pouring-gate and a crown-core re-

cess, and a metal crown-core seated in said recess and having internally-vented prong-channels formed therein. 15

5. In a mold for finger-rings, a substantially conical crown-core of metal, having a central opening and radial vent-slits extending from said opening to substantially all the longitudinal portions of prong-channels 20 formed in the outer portion of the core-body.

H WALTER ALEXANDER.
